KEY HOLDER

Kenneth A. Valentine, Mesilla Park, N. Mex.

Application December 7, 1945, Serial No. 633,424

15 Claims. (Cl. 70—456)

1

This invention relates to key holders designed to be carried in the pocket or handbag and to house a plurality of keys for individual and convenient manipulation without detachment from the holder.

It is the primary object of the present invention to devise a supporting structure embodying a single rod or its equivalent for interconnection with a plurality of keys in such manner that the keys may lie compactly in contiguous lateral relationship, in parallelism, with each arranged at an oblique angle to the rod and its supporting means.

It is another major object to provide a key carrier in which the keys are maintained substantially in parallelism between two side members, which include a single suspension member for the group of keys and which permit ready voluntary detachment of any one or all of the keys.

A further important object resides in the provision of a key carrier embodying an elongated element designed to pass loosely through the key handles, and a related element so disposed as to engage the edges of said handles and urge them laterally into inclination with respect to said elongated element, while permitting each key to be swung individually relative to the others.

There are other objects comprising details of construction of the key supporting means, their relationship to each other and their relationship to a retaining cover or housing. These and the foregoing objects should become clearly apparent after a study of the following description in conjunction with the accompanying drawings, in which:

Fig. 1 is a face view of a preferred form of my invention, completely assembled and with keys shown in place, the cover being opened to permit individual key oscillation;

Fig. 2 is a top plan view of the device of Fig. 1;

Fig. 3 represents a section taken approximately along the plane of line 3—3, Fig. 2 but showing a single key for clearness of illustration;

Fig. 3^a is a view similar to Fig. 3 but showing a modified form of key suspension bar;

Fig. 4 is a face view of the same embodiment, detached from the cover and with keys and their supporting bar removed;

Fig. 5 is a front elevational view of the supporting bar seen in Figs. 1—3;

Fig. 6 is a top plane view of the element of Fig. 5;

Fig. 7 shows a top plane of the device of Fig. 4;

Fig. 8 is a face view of a second embodiment of

2

my invention, detached from the cover and with keys removed;

Fig. 9 is a top plan view of the unit seen in Fig. 8;

Fig. 10 is a front elevational view of one of the component parts of Figs. 8 and 9;

Fig. 11 is a frontal view of the other component part, complementary to that of Fig. 10;

Fig. 12 represents a section taken substantially on the plane of line 12—12, Fig. 8;

Fig. 13 represents a section taken approximately along the line 13—13, Fig. 8;

Fig. 14 is a view similar to Fig. 8, but showing a third embodiment of my invention;

Fig. 15 is a face view of a detached unit of the combination seen in Fig. 14;

Fig. 16 is a face view of the other separated unit of the combination shown in Fig. 14;

Fig. 17 is a top plan view of the combination seen in Fig. 14;

Fig. 18 represents a detail section taken along the plane of line 18—18, Fig. 14;

Fig. 19 represents another detail section taken on the line 19—19, Fig. 14; and

Fig. 20 is a section taken substantially upon the plane of the line 20—20, Fig. 14.

With continued reference to the drawings, and with particular reference first to Figs. 1 to 7, there is shown a flexible housing sheet of leather or like material 21, foldable on the lines 22 and including an end tab 23. This tab 23 has an attached fastening element 24 for cooperation with a complementary element 25 to hold the sheet in the form of a housing when it is folded around the keys and their supporting structure, about to be described.

A group of keys, designated in entirety by the numeral 26, and each of conventional design comprising a head or handle having an aperture, as shown, is carried by a substantially rigid framework which includes a plate 27 that has integral wings 28 for laterally confining the group of keys. These wings are bent into parallelism at an oblique angle preferably acute—to the plate 27, and have their ends rounded and so disposed as not to extend beyond the edges of the housing sheet 21. The plate 27 is secured as, for example, by rivets 30 to the sheet 21, these rivets also serving to attach a second and smaller plate 31. The latter is bent rearwardly to form a spring element 32 that thrusts the sheet 21 rearwardly and also urges the key handles forwardly so that the keys tend to assume a properly inclined position.

The tops of the wings 28 are slotted at 33, and

intermediate their ends are provided with holes 34. A bar 35 fits into the slots 33, and has legs 36 extending downwardly and bent inwardly to provide elements 37 for reception by the holes 34. These legs 36 are inclined to the same degree as the wings 28 so as to fit closely against the outer sides thereof. The bar 35, upon which the keys are carried, preferably is flat and rectangular in cross section as shown in Fig. 3, or approximately elliptical as shown at 35^a in Fig. 3^a; but it may be of any shape that will permit the keys to assume the illustrated angle of tilt and to swing, individually, upwardly from the others into position for insertion in a lock.

The manner of addition and removal of keys should now be fairly obvious. By springing the legs 36 apart, the bar 35 can be removed from the framework. Key handles can be slid over the legs 36 onto the bar, and likewise readily removed, and the bar can thereafter be replaced by snapping the elements 37 into the holes 34.

Figs. 8 to 20 show two further embodiments in which the housing sheet 21 and the group of keys are omitted for simplicity of illustration.

The form shown in Figs. 8 to 13 comprises a backing plate 41 having a spring member 42 (corresponding to the element 32 of Fig. 4) riveted or otherwise attached thereto. The plate 41 has an integral inclined wing 43 with its outer edge bent backwardly as shown, for a purpose presently perceivable. The plate also has an integral and correspondingly inclined shorter wing 44, bent at its outer edge, at 45 to form a channel.

A second elongated wing 46, complementary to the wing 43, is vertically slideable downwardly into the channel just described, and it may have a cut-out tongue 47 designed to enhance the frictional fit. The latter is preferably bent outwardly to form a stop member 48 engageable with the lower edge of the wing 44 to releasably hold the wing 46 from upward movement. The wing 46 also carries, as a unit, a small plate 50 welded or otherwise secured to its outer side, this plate having an integral bar 51 corresponding to the bar 35 of Figs. 1, 2, 3, 5 and 6. The bar 51 may extend through a suitable hole in the wing 46, or it may be moved into position through a rearwardly extending slot.

The bar 51 has a leg 52 twisted relative thereto to place it in parallelism with the wing 46, and at its lower end the leg has a horizontal extension 53 in the same plane, terminating in a forwardly bent portion 54 that is complementary to a slot 55 in the wing 46.

After "stringing" keys over the leg 52 and onto the bar 51 (see the unit of Fig. 11), the unit of Fig. 11 is pushed downwardly into the unit of Fig. 10 to form the complete assembly of Figs. 8 and 9. At the time the member 45 engages the stop 48, the bent portion 54 snaps into the slot 55. To separate the parts, portion 54 is pushed out of the slot 55, the stop member 48 raised, and the units of Figs. 10 and 11 are pulled apart.

The embodiment of Figs. 14 to 20 differs chiefly from that just described in that there are two units which are separable laterally instead of vertically. In this embodiment there is an inclined wing 57, generally similar to wing 46 of Fig. 11, having an attached plate 59 with an integral bar 60, corresponding to the bars 35 and 51 previously described. The bar 60 terminates in a slightly bent latching tab 61.

Integral with, or secured to the wing 57 in any suitable manner is a plate 62, corresponding to the plates 27 and 41. This plate has its upper

and lower edges bent over at 63 in the same direction to provide a horizontal guide and slide-way for a purpose presently apparent. A spring plate 64, corresponding to plates 32 and 42, is riveted or otherwise attached to the upper rear surface of the plate 62.

Complemental to the unit of Fig. 16 is the unit of Fig. 15, comprising a second wing 65 which has an integral offset plate 66 having a cut-out forming a tongue 67, the latter being bent laterally as shown (Fig. 19) for latching cooperation with a slot 68 in the plate 62. As seen in Figs. 14 and 18, the tab 61 is designed to yieldingly latch into a slot 70 in the upper end of the wing 65.

The modus operandi of this third form of my invention is believed to be fairly evident. The cross bar 69 carries the keys, which are added to the unit seen in Fig. 16. This unit then is detachably united to that of Fig. 15 by pushing them together, laterally and edgewise, until the elements 61 and 67 latch, respectively, into the slots 70 and 68. Removal of the keys is accomplished in reverse fashion.

Since, in all of the embodiments of the invention shown and described, the wings project upwardly from the basal part, an opening or space is provided above the basal part which permits the handle parts of the keys to project rearwardly beyond the plane of the basal part and to come into direct contact with the cover or housing of the holder, thus enabling the total thickness of the entire holder to be determined by the keys and cover alone.

Also, in all embodiments of the invention as shown and described, the key suspension member is disposed at or near the upper extremities of the wings or lateral supporting members. Such a disposition of this element of the holder has the advantage that it permits the keys themselves to be suspended at the uppermost point in the holder so that the total length of the holder need be only long enough to accommodate the contained keys.

The present invention further provides a key holder in which the key retaining element and its supporting elements hold the keys in a contiguous overlapping relation so that the total width of the holder and the contained keys is determined by the distance between the supporting elements for the key retaining element, which supporting elements occupy the extreme lateral positions in the holder.

There obviously are many ways in which the present invention may be modified, in details as well as general assembly, without departing from the spirit of the invention, and such modifications are intended to be included within the scope of the claims.

What is claimed is:

1. A key holder comprising a backing member having a pair of spaced, rigid parallel wings rigid with and arranged at an oblique angle to said backing member and spaced apart to confine a plurality of keys between them, and an elongated key suspension element connected between said wings.

2. A key holder comprising a backing member having a pair of spaced, parallel wings arranged at an oblique angle to said backing member and spaced apart to confine a plurality of keys between them, and an elongated key suspension element connected between said wings, said suspension element being shaped to pass readily through the apertured handles of a plurality of

keys and to permit them to tilt laterally, and means attached to said backing member in a position to engage the key handles to urge them outwardly from said backing member and thus tend to urge the keys into a laterally tilted group.

3. A key holder comprising a plate carrying rigid wings arranged in parallelism and connected rigidly to said plate and inclined obliquely thereto, a bar interconnecting said wings and designed to receive a plurality of apertured key handles, and means associated with said bar and said wings to permit convenient addition and replacement of the keys.

4. In a keyholder, the combination of a key supporting framework comprising a flat plate having a pair of rigid parallel wings connected rigidly to and projecting from one side thereof and inclined at an approximately acute angle to said plate, and a cross bar removably connected to said wings and shaped to loosely carry a plurality of apertured keys.

5. In a keyholder, the combination of a key supporting framework comprising a flat plate having a pair of rigid parallel wings projecting from one side thereof and inclined at an approximately acute angle to said plate, and a cross bar removably connected to said wings and shaped to loosely carry a plurality of apertured keys, said cross bar being flattened on its horizontal dimension, said wings having slots in their adjacent opposed ends for reception of the ends of said bar, said bar having extensions bent flatwise and lying against surfaces of said wings, and said wings and said extensions having complementary means for releasably latching them together.

6. In a key holder, the combination of a framework comprising a plate carrying a wing arranged at an angle thereto, a second complementary wing carrying a cross member designed for detachable connection with the first mentioned wing, and shaped to suspend a plurality of apertured keys, and coacting slidably engageable means on said plate and said second wing for releasably holding said plate and said second wing in united relationship to form said framework.

7. The combination defined in claim 6, wherein said wings in the assembled framework are in parallelism and disposed at an oblique angle to said plate.

8. A key holder comprising a basal part, a pair of rigid projections spaced laterally and extending rigidly upwardly from said basal part and lying in parallel planes at acute angles to the plane of the basal part, and a key suspension member extending between the upper portions of said projections and having a cross-section which is lesser on its horizontal diameter than on its vertical diameter to extend through holes in the key handles and support the keys while they lie between said projections and at an acute angle to the plane of the basal part.

9. A key holder according to claim 8, wherein said key suspending member is ellipsoidal in cross-section.

10. A key holder comprising a basal part, a pair of projections extending upwardly therefrom at the opposite ends thereof beyond the

upper edge of said basal part, said projections being bent forwardly from said basal part, a key-suspension member extending between said projections above said basal part to loosely receive apertured handle parts of keys and to support the latter with their handle parts extending rearwardly above the basal part, and a yieldable element secured to the basal part and extending upwardly beyond the upper edge thereof and engageable directly with said rearwardly extending handle parts of the keys to urge the keys to an acute angle relatively to said key-suspension member.

11. A key holder comprising a basal part, a pair of rigid supporting elements extending upwardly therefrom at the extreme opposite sides thereof and projecting rigidly forwardly from said basal part in planes at an acute angle to the plane thereof, and a key retaining element extending between and connecting said supporting elements for suspending keys while held in overlapping relation by said supporting elements.

12. A key holder comprising a basal part having a wing rigidly united therewith and extending forwardly from one lateral edge thereof at an acute angle thereto, a second part carrying a wing complementary to the wing on the basal part, a key suspension member carried by said second part, and slidably engageable means on said parts for guiding them for relative vertical movement to bring the key suspension member into cooperative relation with the wing on the basal part.

13. A key holder according to claim 12, including a stop member on one of said parts engageable with the other of said parts to detachably retain said parts in cooperative relation.

14. In a key holder the combination of a framework comprising a plate having flat wing rigidly united thereto and arranged at an angle thereto, an elongated key-suspending element connected in perpendicularity to said wing, a second wing having an integral extension designed to slide edgewise and laterally into connection with said plate, and means on said second wing for detachably receiving the free end of said key-suspending element.

15. The combination defined in claim 14, wherein said wings are parallel, and inclined obliquely to said plate and said extension to provide lateral confining surfaces for any group of keys carried by said element.

KENNETH A. VALENTINE.
